UNITED STATES PATENT OFFICE.

FRANK E. WOLCOTT, OF HARTFORD, CONNECTICUT.

AUTOMOBILE-LAMP.

1,226,294.

Specification of Letters Patent.

Patented May 15, 1917.

Application filed June 18, 1916. Serial No. 103,981.

To all whom it may concern:

Be it known that I, FRANK E. WOLCOTT, a citizen of the United States, and a resident of Hartford, in the county of Hartford and State of Connecticut, have invented a new and Improved Automobile Lamp, of which the following is a full, clear, and exact description.

This invention relates to head lights for vehicles, and has particular reference to removable or adjustable lamps adapted especially for automobile practice.

Among the objects of the invention is to provide a lamp comprising a conventional type of casing adapted to be held in stationary position by any suitable brackets or supports and having a window or lens at its front, and also being provided within the casing with a movable reflector adapted to throw the light normally downwardly at some convenient distance closely in front of the vehicle.

Another object of the invention is to provide a lamp reflector pivoted on a horizontal axis adjacent the front edge or end thereof remote from the optical center of the reflector, means being provided whereby the operator at a distance may swing the reflector up or down as may be desired around its axis.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section showing my improved automobile lamp with the parts in normal position, or so arranged as to throw the light downwardly in front of the vehicle;

Fig. 2 is an enlarged vertical section of the controlling parts of the lamp, but with the parts in changed position from that of Fig. 1;

Fig. 3 is a vertical transverse sectional detail on the line 3—3 of Fig. 2; and

Fig. 4 is a detail of a modification described below.

I employ a stationary casing 10 of any

conventional or well known type, the same having a lens or window 11 secured to the front thereof by means of an outer rim 12. The front rim portion of the casing 10 comprises an inwardly turned roll or bead 10^a against which the outwardly directed flange 13' of a supplemental segmental reflector 13 is held by the lens and outer rim 12.

The reflector 14, preferably of a parabolic type, is pivotally connected on a horizontal axis at 15 to the inner surface of the spherical flange 13. The axis of the pivots 15 lies close to the front edge of the reflector and is perpendicular to the longitudinal axis of the reflector, the lamp 16 being fitted in a socket 17 near the rear end of said longitudinal axis. The lower half of the reflector below the plane intersecting the pivotal axis of the reflector and the center of the lamp, is provided with its front edge lying in a plane perpendicular to the last mentioned intersecting plane. In other words, with the reflector adjusted so as to project the light directly ahead, the bottom edge of the reflector will lie substantially against the bottom half of the lens 11, and with the focal center of the reflector lying in the horizontal longitudinal axis of the reflector, this axis being indicated by the dotted line 18 representing the direction in which the intense light is projected.

The upper half of the reflector is beveled as indicated at 19 whereby the reflector may be tilted upwardly and forwardly around the axis 15 to tilt the axis 18 and cause the light to be projected downwardly upon the roadway. In either position of the reflector, the exposed portion of the flange 13 constitutes in effect a continuation of the reflecting surface of the reflector.

The means I prefer to use to control the position and action of the reflector includes a tubular support 20 fixed in stationary position in the back part of the casing 10. The rear end of this support is screwthreaded and tapped into a hole 21 at a convenient place for the attachment of the electrical connections, and is locked in place by means of a lock nut 22. On the inside of the casing 10, the support is curved upwardly and carries a vertically reciprocating plunger 23. A flexible tube 24 is passed into the lower open end of the support 20 and is secured to a partition 25 at the lower end of the ver-

tical portion of the support. The plunger is hollow and houses a spring 26 which bears at its lower end against the partition 25 and at its upper end against the head 23' of the 5 plunger. A wire or rod 27 extends through the flexible tube 24 and through the spring, and is connected at its upper end to the head 23' of the plunger.

The socket 17 mentioned above is in the 10 nature of a hub projecting rearwardly from the reflector 14, and is adapted to receive the base 28 of the lamp. The electric wires 29 to the lamp are led upwardly through the hollow lower end of the support 20 and 15 thence laterally through a side opening 30 within the main casing 10.

As shown best in Figs. 2 and 3, the hub or socket 17 is surrounded or embraced by a ring or yoke 31 spaced from the socket to 20 allow freedom of action, but the space is effectively closed by means of spring cushions 32, shown as four in number and arranged both above and below, and at the right and left sides.

25 The spring 26 is arranged so that it will tend to move the plunger and yoke 31 in one direction automatically. This movement is in a straight line and vertical, as shown in Fig. 2. Movement in the opposite direction 30 is accomplished through the wire 27 in opposition to the force of the spring 26. Without unnecessarily limiting the operation, I suggest that the automatic action through the spring be in the direction to elevate the 35 lamp, and cause the rays of light to be thrown downwardly, as shown in Fig. 1, and the draft upon the wire or rod 27, which may be accomplished either by hand or foot means, (not shown) will be for the 40 purpose of throwing the lamp downwardly, or so that the rays of light therefrom will be projected in a horizontal beam. Since the reflector and lamp are moved around the axis 15 in the arc of a circle and the yoke 45 31 is moved in a vertical line only, being held from movement in other directions through the plunger and surrounding support or barrel, it is necessary to provide a certain amount of freedom of action between the yoke and the hub 17. This 50 freedom of movement is provided for by the springs 32. In other words, the yoke always embraces the socket or hub 17, so as to actuate the reflector either up or down, 55 and the springs provide for a substantial constant contact to prevent rattling or lost motion. The wire 29 is so arranged that it does not interfere with the adjustment of the lamp and reflector.

60 In the modified form, shown in Fig. 4, the support 20' is shown as straight and extending vertically through a hole 21 in the rear portion of the casing. This support is locked in position by means of the nut 22 65 drawing upon a pair of tubular washers 20*

on the inside and outside of the casing. This form of support is better adapted for lamp casings where less room is provided between the reflector and the main casing. Otherwise the structure and operation are 70 the same, however, as already set forth.

I claim:

1. In a device of the character set forth, the combination of a stationary casing having at its front portion a rearwardly projecting inner flange, a lens secured against the front portion of the flange, a parabolic reflector within the casing and pivoted at its front edge on a horizontal axis to said flange, said reflector being so disposed that 80 the front edge of its lower half is adapted to abut against the lens when the axis of the reflector is horizontal, and being beveled at its upper half so that it will abut against the upper portion of the lens when the axis 85 of the reflector is tilted to cause the light to be projected in a beam downwardly in front of the lamp, and means projecting through the rear portion of the casing to conduct electricity to the lamp and control 90 the position of the reflector.

2. In an automobile lamp, the combination of a casing having attached at its front an inner rearwardly projecting curved flange, a parabolic reflector within the casing pivoted on a horizontal axis to said flange, the upper and lower halves of the reflector having their front edges arranged in planes at an angle to each other and so disposed that said flange constitutes a continuation of the reflecting surface of the reflector according to the position of the reflector, a lamp fitted in the rear portion of the reflector in the focal center thereof, a stationary support fitted in the rear portion 105 of the casing and extending thence upwardly between the reflector and the casing, a plunger slidably in said support and embracing a portion of the reflector, means acting upon the plunger to move it automatically in one direction, and other means 110 acting in opposition to the automatic means to move the reflector in the opposite direction.

3. In an automobile lamp, the combination of a casing having a hole at the back portion, a stationary support fitted rigidly in said hole and having a tubular lower end, the upper end of the support extending vertically, a plunger slidably fitted in the vertical end of the support, a spring acting upon the plunger to move it in one direction, manually controlled means acting upon the plunger to move it in the opposite direction, a yoke connected to the upper end of 115 the plunger, a reflector pivoted on a horizontal axis at the front portion of the casing, a lamp carried by the rear portion of the reflector, said reflector including a socket for the lamp, said socket being em- 120 125 130

braced by said yoke, and means extending through the hollow lower end of the support to conduct electricity to the lamp.

4. In an automobile lamp, the combination of a main support, a reflector pivoted at its front edge in said support and movable at its rear end vertically in the arc of a circle, said rear end including a rearwardly projecting extension, a lamp fitted 10 in said extension, and means coöperating with said extension to control the pivotal movements of the reflector, said last mentioned means including a ring loosely embracing the extension and having spring 15 contacts filling the space between the ring and the extension, said ring being movable vertically.
5. The combination of a stationary casing, a tubular support fixed in the rear portion of the casing, the lower end of the support being curved and the upper end of the support being straight and vertical, the curved portion of the support being provided with a lateral hole, a plunger telescopically connected with the upper end of the support, a spring acting upon the plunger to project it upwardly in a vertical 20 line with respect to the support, a yoke se-
- 25

cured to the upper end of the plunger, a reflector pivoted in the casing and having at 30 its rear end a socket projecting rearwardly over the plunger and through the yoke, a lamp fitted in the socket, spring contacts between the yoke and the socket extension, and lamp wires leading through the lower 35 end of the support and thence through the lateral hole to the lamp socket between the casing and the reflector.

6. The combination of a fixed casing, a rigid support fixed therein and comprising 40 a tubular curved lower end and a vertical straight upper end, a flexible tube extending through the lower end of the support and connected to the middle portion thereof, a plunger telescopically connected with 45 the upper end of the support, a spring acting upon the plunger to move it in one direction, a wire connected to the plunger and extending thence outwardly through the flexible tube acting upon the plunger in 50 opposition to the spring, a yoke connected to the upper end of the plunger, and a movable reflector within the casing having a rearward extension embraced by said yoke, substantially as set forth.

FRANK E. WOLCOTT.
